UNITED STATES PATENT OFFICE.

OSKAR LASCHE, OF CHARLOTTENBURG, GERMANY, ASSIGNOR TO GENERAL ELECTRIC COMPANY, A CORPORATION OF NEW YORK.

STARTING MECHANISM FOR MULTICYLINDER INTERNAL-COMBUSTION ENGINES.

1,212,779.

Specification of Letters Patent. Patented Jan. 16, 1917.

Application filed February 17, 1915. Serial No. 8,718.

To all whom it may concern:

Be it known that I, OSKAR LASCHE, a subject of the King of Saxony, residing at Charlottenburg, Germany, have invented 5 certain new and useful Improvements in Starting Mechanism for Multicylinder Internal-Combustion Engines, of which the following is a specification.

The present invention relates to multi- 10 cylinder internal combustion engines of the high compression type, in which the scavenging or charging air is furnished by a suitable pump driven by the engine.

The object of the invention is to provide 15 an improved arrangement for starting such engines.

For a consideration of what I believe to be 20 novel and my invention, attention is directed to the accompanying description and the claims appended thereto.

In the accompanying drawing Figure 1 is 25 a longitudinal section of a multi-cylinder combustion engine; Fig. 2 is a cross-section on the line 2—2, Fig. 1; Fig. 3 is a top plan view, and Fig. 4 shows a modification.

The working cylinders 1, 2, 3 and 4 each 30 contain two oppositely moving pistons 5, 6, which act on the same crank shaft, the upper pistons controlling the exhaust ports 7 and 35 the lower pistons the scavenging or air charging ports 8, to which air is admitted from the receiver 9. The scavenging pump 10 delivers air into the receiver 9 through the valves 11.

The exhaust ports 7 are connected with a 40 common header or manifold 12 by the branch pipes 13. Some of these, for example the two from the cylinders 3 and 4, are provided with throttle valves 14 by means of which the pipes can be entirely opened or closed or 45 more or less throttled. The valves may be operated by a hand lever 15 connected by rods 16 with arms 17 on the valve spindles. The other cylinders, that is in the present 50 instance the cylinders 1 and 2, are also provided with valves 19 for introducing compressed air for starting the engines. All the working cylinders are provided with fuel injectors 18.

The operation is as follows: Compressed 55 air is admitted to the working cylinders 1 and 2 by the starting valves 19 at the proper intervals, while at the same time the exhaust

60 pipes of the cylinders 3 and 4 are throttled or closed by means of the valves 14. The 55 crank shaft, rotated by the impulses of the compressed air in the cylinders 1 and 2, transmits its motion to the pistons in the cylinders 3 or 4, and also to the piston of the scavenger pump 10, and accelerates them 60 uniformly. The air discharged by the pump into the receiver 9 rises in pressure during the period of starting; thereby also raising the compression temperature in the working cylinders to a point above that attained during normal running, because the scavenging air, which in quantity is sufficient for all 65 four cylinders, is now used only in two of them, 1 and 2, by reason of the throttling of the exhaust from the other two, 3 and 4. 70 Consequently, only part of the air can escape, and the remainder increases in pressure and becomes highly heated.

Whenever the scavenging ports of the cylinders 3 and 4 are opened, highly heated air 75 from the receiver enters said cylinders so that in a short time a final compression temperature is attained therein sufficiently high for operation with fuel. It will be noted that since the exhausts of the two cylinders 80 are throttled while starting, their contents are not replaced on each successive cycle by air from the receiver, but that on successive strokes the same air is compressed, a little more air being added to it from the receiver, 85 thus raising its initial pressure according to the pressure in the receiver. This air will be added since the receiver pressure will be slightly above the cylinder pressure at the time when the scavenging ports open. As 90 soon as these cylinders begin to fire, their exhausts are opened by turning the valves 14, and coincidently therewith the supply of compressed starting air is shut off by valves 19 from the cylinders 1 and 2, and fuel is injected, either immediately or after a few dead strokes. These cylinders will begin to fire very quickly, because during their operation by compressed air the hot scavenging air has entered them after every power 100 stroke, and this has partially neutralized the cooling effect of the expanding starting air.

Instead of a rigid connection between the valves 14 and the lever 15, a yielding 105 connection may be used, as shown in Fig. 4,

where a spring 20 is interposed in the line of transmitting elements. A nut 21 enables the tension of the spring to be adjusted.

In accordance with the provisions of the 5 patent statutes, I have described the principle of operation of my invention, together with the apparatus which I now consider to represent the best embodiment thereof; but I desire to have it understood that the 10 apparatus shown is only illustrative, and that the invention can be carried out by other means.

What I claim as new and desire to secure by Letters Patent of the United States, is,—

15 1. In an internal combustion engine, the combination of a plurality of cylinders having exhaust and scavenging ports, a receiver communicating with the scavenging ports, fuel admission means, valve means for supplying starting air to some of said cylinders,

and means for throttling or closing the exhausts of the other cylinders during the starting period.

2. In a high compression internal combustion engine, the combination of a plurality of cylinders having exhaust and scavenging ports, a common receiver communicating with the scavenging ports of all the cylinders, a pump for supplying air to the receiver, an exhaust manifold, pipes connecting the exhaust ports thereto, air starting valves connected with some of said cylinders, and shut-off valves in the pipes of the other cylinders.

In witness whereof, I have hereunto set my hand this 18th day of January, 1915.

OSKAR LASCHE.
